UNITED STATES PATENT OFFICE.

JOHANN FRIEDRICH CHRISTOPHER GRÜN, OF HAMBURG, GERMANY.

DEVICE FOR TURNING MUSIC-SHEETS.

SPECIFICATION forming part of Letters Patent No. 444,380, dated January 6, 1891.

Application filed April 8, 1890. Serial No. 347,153. (No model.)

To all whom it may concern:

Be it known that I, JOHANN FRIEDRICH CHRISTOPHER GRÜN, a subject of the Emperor of Germany, and a resident of Hamburg, 5 Germany, have invented a new and useful Improvement in Devices for Turning Music-Sheets, of which the following is a specification.

The object of this invention is to provide 10 a device for mechanically reversing music-sheets while playing, which is operated by pulling a cord or depressing a pedal connected therewith.

Reference is had to the accompanying drawings, in which like letters designate like parts.

Figures 1 and 2 are perspective views, and Figs. 3 and 4 end views from the left and right, respectively, of the improved device.

The prismatic guide-piece A, serving to 20 carry the mechanism, is secured to the music-desk P by means of two holders a, which are introduced into tubes b provided on the desk, said guide-piece being therefore adjustable to the thickness of the respective music-book N.

25 In the piece A referred to is securely guided a slide-block B, to the under side of which is attached an eye or loop c, serving to receive the cord d and a nut e. Said loop and nut project through slots in the bottom side 30 of the guide-piece, on which is provided, between two angle-pieces, a core or rod g, surrounded by a helical spring h. On said core slides the nut e on the forward movement of the slide-block, and compresses the spring h, which, on the cord or pedal being released, 35 throws back the slide-block.

On the upper side of the block is provided, revoluble about a pin i, the fold-producer k, the nave of which is rigidly connected with 40 the pinion l, gearing into a rack-bar m. At the other end of the slide-block is pivoted, in a block n, the sheet-reverser, consisting of the turning-rod O and the toothed segment O', adapted to engage into a toothed bar p after the fold-producer has made one quarter-revolution, and then to complete the stroke simultaneously with the latter, the fold-producer, however, moving in the horizontal and the reverser in the approximately vertical 45 plane.

The mechanism for turning back music-sheets for repetition consists of a second reverser q, turning in a block v. The latter is mounted on a short slide-block C, likewise 50 movable in piece A, and adapted to be coupled

with the longer slide-block B by aid of a pivoted pin s, which is connected with a two-armed lever t, having its fulcrum in block v. The two slide-blocks are coupled and uncoupled by respectively depressing the knob 60 t' or t''. The toothed segment of the reverser q moves with the forward stroke in a toothed bar u, thereby causing the reverser q to be moved in a similar manner as the turning-rod O.

65 The improved music-sheet reverser is operated as follows: By pulling the cord d by means of the pedal or otherwise the fold-producer k is turned to the left and the music-sheet bulged up, Fig. 1. The reverser O, 70 which now rises, enters into the bulging produced, turns the sheet over, and, owing to its peculiar movement, smooths the same, while the fold-producer completes its revolution as far as two hundred and seventy 75 degrees. In this final position, which is illustrated in Fig. 2, the slide-block C can be coupled with block B by depressing the knob t', thereby causing the pivoted pin s to catch in any suitable manner into block B. On 80 releasing the cord the repetition-reverser q is turned to the right with the reverser O, which resumes its inoperative position, and all sheets lying on the repetition-reverser are turned back simultaneously.

85 What I claim is—

In a device for turning music-sheets, the combination, with a fold-producer k, revoluble about pin i, and pinion l, rigidly connected thereto and gearing with rack-bar m, 90 of slide-blocks B and C, adapted to be moved by aid of a pedal, cord, and spring device in a guide-piece A, a sheet-reverser pivoted in a block n, and consisting of a turning-rod O and a toothed segment O', adapted to gear 95 into a toothed bar p, a repetition-reverser mounted on slide-block C, and consisting of a reversing-rod q, connected with a toothed segment gearing into a rack-bar, a two-armed lever t, having its fulcrum in a block v, and 100 a pivoted pin s, adapted to engage the slide-block B, substantially as and for the purpose set forth.

In testimony whereof I have signed this specification in the presence of two subscribing witnesses.

JOHANN FRIEDRICH CHRISTOPHER GRÜN.
